OIL BURNER.

APPLICATION FILED APR. 4, 1904.

2 SHEETS—SHEET 2.

UNITED STATES PATENT OFFICE.

ROSS B. DE REMER AND JOSEPH B. ROBINSON, OF LOS ANGELES,
CALIFORNIA.

OIL-BURNER.

SPECIFICATION forming part of Letters Patent No. 779,029, dated January 3, 1905.

Application filed April 4, 1904. Serial No. 201,405.

To all whom it may concern:

Be it known that we, ROSS B. DE REMER and JOSEPH B. ROBINSON, citizens of the United States, residing at Los Angeles, in the county 5 of Los Angeles and State of California, have invented a new and useful Oil-Burner, of which the following is a specification.

This invention relates particularly to oil-burners designed for use in stoves, particularly 10 cooking-stoves, and is designed to utilize a good quality of distillate as fuel.

One object of the invention is to provide a burner which is simple in construction and which will produce, with a proper mixture 15 of air and gas, perfect combustion, with no smoke and with a minimum amount of distillate.

Another object is to provide means for effectively 20 cleaning the burner without removing any of the parts of the stove or burner and without using a scraper or other tool, the entire burner, together with the cleaning device, being self-contained.

Another object is to so arrange the burner 25 in the fire-box of the stove and so construct the parts of the burner, which are embodied to an extent in the structure of the fire-box, as to limit the introduction of air to the fire-box to a definite point, so located with respect to 30 the burner as to supply oxygen to the flame from the burner at the most effective point of the flame and promote combustion to the highest degree.

Other objects of the invention will appear 35 from the following description.

The accompanying drawings illustrate the invention.

Referring to the drawings, Figure 1 is a sectional view taken vertically through a stove 40 longitudinally of the fire-box looking from the rear of the stove toward the front, showing the burner in place, the burner being shown in elevation. Fig. 2 is a sectional view on line X² X², Fig. 1. Fig. 3 is a perspective of the lining-plate. Fig. 4 is a sectional view through the burner, enlarged and removed from the fire-box. Fig. 5 is a detail view of a portion of the shank of the double-threaded cleaning-pin. 45

1 designates the body of the stove, having the fire-box 3, which is provided with the usual 50 lining of refractory material 4.

5 is the top of the stove, having lids 6. The bottom of the fire-box and front of the fire-box are lined by a plate 7, formed, preferably, of a single piece of sheet metal, the vertical 55 leaf of which has an air-slot 8 and the bottom leaf of which has an orifice 9.

The edges of the lining-plate 7 closely fit with the lining of refractory material 4, so that the fire-box is substantially air-tight, air 60 only being permitted to enter at the slot 8. Air is admitted through the orifice 9 to the burner proper, which comprises a head 10, consisting of a hollow cylindrical ring 11, having a central web 12. The upper wall of 65 the head is provided with jet-orifices 13, suitably spaced. A thimble 14 is screwed to the head 10 and communicates with the interior thereof, and screwed to the thimble 14 is a T 15, the lower leg of which closely fits the 70 bottom leaf of the lining-plate 7, projecting through the orifice 9. Screwed to the T 15 is a gas-nozzle 16, having a relatively small gas-passage 17, extending rearward from its point and communicating with a larger chamber 18, in the walls of which are formed a conical shoulder 19 and an abrupt preferably 75 square shoulder 20.

A cleaning-pin 21, which is of a size to closely fit the gas-passage 17 and which is adapted to 80 be pushed into and through the gas-passage 17, is carried on the end of a shank 22, which traverses the chamber 18 and is provided with a conical shoulder 23 and an abrupt preferably 85 square shoulder 24, which shoulders are respectively adapted to abut against the shoulders 19 and 20, before mentioned. At the rear of the shoulder 24 the shank 22 is enlarged in diameter and is screw-threaded, having, preferably, a double thread, which is 90 received by the rear portion of the gas-nozzle 16.

A hand-wheel 25 is provided on the end of the shank 22 for screwing the shank forward or backward to force the cleaning-pin 21 into 95 and out of the gas-passage 17 to clean the

same. A packing, preferably of asbestos 26, is provided around the shank 22 to prevent the escape of gas, being confined in place by suitable stuffing-box 27.

- 5 A tubular retort, comprising a cylindrical member 28, is arranged above the head 10. One end of the retort communicates, through a relatively small pipe 29, with the chamber 18 of the gas-nozzle, while the other end of 10 the retort communicates by a pipe 30 with a needle-valve 31 for regulating the supply of distillate or other fuel to the retort.

32 is a pipe for conveying the supply of fuel to the needle-valve. A specific construction of 15 the needle-valve 31 is immaterial to the present invention. Any good form of needle-valve is well adapted for the purpose, and as the needle-valve *per se* forms no part of the present invention and as needle-valves are 20 well known in the art it is not necessary to describe the needle-valve in detail.

Referring to Fig. 1, it will be seen that the burner just described is arranged within the fire-box 3 in such a manner that the retort 28 25 lies between the top of the stove and the burner-head and that the shank of the gas-nozzle 16 extends through the end of the fire-box, as shown, so that the hand-wheel 24 is within convenient reach. The pipe 30 also 30 extends through the other end of the fire-box, leaving the needle-valve 31 in a convenient position for regulating the supply of fuel to the burner. It will also be noticed that the air-slot 8 is so arranged that it is about on a 35 line with the upper rim of the burner-head 10, so that air entering in a sheet through the slot mixes with the flame issuing from the orifices 13.

In operation the needle-valve 31 is opened 40 to permit oil to flow into the retort 28 and is first heated by means of waste or kindling until sufficient gas has been formed to start the burner. It will be noticed that the pipe 29 communicates with the retort 28 at the 45 highest point of the retort. This prevents any oil which may not have been formed into gas from running down from the pipe 29. As soon as gas has been formed it passes through the pipe 29 into the gas-nozzle 16 50 and issues with considerable velocity through the passage 17. As it issues from the passage 17 it mixes with air which enters through the lower leg of the T 15, the air being sucked in through the T by the issuing jet 55 of vapor in a manner similar to the action of an injector. The mixture of gas and air then passes into the head 10, from whence it issues through the orifices 13 and mingles with the air which enters the fire-box 60 through the slot 8, and the flames from the burner-head serve to form the distillate in the retort into a gas, this action being continuous after the burner has been started.

The small passage 17 may readily be cleaned

at any time by screwing in the cleaning-pin 65 21, the blunt end of which forces out any solids which may have collected in the orifice.

While we have shown and described the preferred construction of our invention, it should be understood that various changes 70 may be made therein without departing from the spirit of the invention.

What we claim is—

1. A fire-box, a lining therefor comprising a single piece of sheet metal the vertical leaf 75 of which has an elongated horizontally-arranged slot, the bottom leaf having an air-orifice, a burner-head within the fire-box having its upper rim about in line with the slot, a retort above the burner-head, means for supplying oil to the retort, and means for conveying gas from the retort to the burner-head.

2. A fire-box, a lining therefor comprising a single piece of sheet metal the vertical leaf 85 of which has an elongated horizontally-arranged slot, the bottom leaf having an air-orifice, a burner-head within the fire-box having its upper rim about in line with the slot, a retort above the burner-head, a gas-nozzle discharging 90 into the burner-head, and means for cleaning the gas-nozzle.

3. A fire-box, a lining therefor comprising a single piece of sheet metal the vertical leaf 95 of which has an elongated horizontally-disposed slot, the bottom leaf having an air-orifice, a burner-head within the fire-box having its upper rim about in line with the slot, a retort above the burner-head comprising a horizontal pipe, a gas-nozzle communicating with 100 the burner-head, a pipe leading from the upper part of the retort to the gas-nozzle, the discharge - passage of the gas - nozzle being smaller than the pipe.

4. A fire-box, a lining therefor comprising 105 a single piece of sheet metal the vertical leaf of which has an elongated horizontally-disposed slot, the bottom leaf having an air-orifice, a burner-head within the fire-box having its upper rim about in line with the slot, a retort above the burner-head comprising a horizontal pipe, a gas-nozzle communicating with 110 the burner-head, a pipe leading from the upper part of the retort to the gas-nozzle, the discharge - passage of the gas - nozzle being 115 smaller than the pipe, and means for cleaning the nozzle comprising a cleaning-stem having a threaded shank.

5. A fire-box, a lining therefor comprising 120 a single piece of sheet metal the vertical leaf of which has an elongated horizontally-disposed slot, the bottom leaf having an air-orifice, a burner-head within the fire-box having its upper rim about in line with the slot, a retort above the burner-head comprising a horizontal pipe, a gas-nozzle communicating with 125 the burner-head, a pipe leading from the upper part of the retort to the gas-nozzle, the

discharge - passage of the gas - nozzle being smaller than the pipe, and means for cleaning the nozzle comprising a blunt cleaning-stem having a threaded shank.

5 6. A fire-box, a lining therefor comprising a single piece of sheet metal the vertical leaf of which has an elongated horizontally-disposed slot, the bottom leaf having an air-ori-
fice, a burner-head within the fire-box having
10 its upper rim about in line with the slot, a re-
tort above the burner-head comprising a hori-
zontal pipe, a gas-nozzle communicating with
the burner-head, a pipe leading from the up-
per part of the retort to the gas-nozzle, the
15 discharge - passage of the gas - nozzle being

smaller than the pipe, and means for cleaning the nozzle comprising a cleaning-stem having a double-threaded shank.

In testimony whereof we have hereunto signed our names to this specification, in the 20 presence of two subscribing witnesses, at Los Angeles, in the county of Los Angeles and State of California, this 28th day of March, 1904.
